(57) **CLAIM**

The ornamental design for a grille of a reclaimer, as shown and described.

DESCRIPTION

FIG. 1 is a front, top, left perspective view of a grille of a reclaimer showing the new design;

FIG. 2 is rear, top, left perspective view thereof;

FIG. 3 is front elevation view thereof;

FIG. 4 is rear elevation view thereof;

FIG. 5 is left side elevation view thereof;

FIG. 6 is right side view thereof;

FIG. 7 is top plan view thereof; and,

FIG. 8 is bottom plan view thereof.

The broken lines of even length shown in the drawings illustrate environmental structure and form no part of the claimed design.

1 Claim, 8 Drawing Sheets
